UNITED STATES PATENT OFFICE

2,435,421

POWER-OPERATED TOOTHBRUSH

Paul H. Blair, Chicago, Ill.

Application March 5, 1943, Serial No. 478,075

1 Claim. (Cl. 15—22)

1

This invention relates to improvements in power-operated tooth brushes, and has for its principal object to provide an improved device of the character described, including two rotary brush elements.

A further object of the invention is to provide an improved construction of a device of the character described, affording removal or assembly of the rotary elements so as to facilitate cleaning or replacement of the rotary elements.

The invention may best be understood by reference to the accompanying drawings illustrating a preferred embodiment thereof, in which—

Figure 1 is a view in longitudinal section of a tooth brush constructed in accordance with my invention, shown in considerably enlarged scale;

Figure 2 is an end view of the device shown in Figure 1;

Figure 3 is a fragmentary bottom view of the brush head with parts broken away to show certain details of construction of the gearing;

Figure 4 is a section taken on line 4—4 of Figure 3; and

Figure 5 is an enlarged detail perspective view of one of the drive gears and coupling means carried thereby.

Referring now to details of the device shown in the drawings, the main parts comprise a frame or holder 10 formed in the shape of a generally rectangular shallow bowl with an elongated handle 11 extending at one end thereof, and having two rotary brush elements 12 and 13 mounted in said frame on longitudinally extending parallel shafts 14 and 15 respectively. The frame 10 consists of side walls 16, 16, bottom wall 17, an outer end wall 18, and an inner end wall 19, to which the handle 11 is secured. The inner end wall extends upwardly above the level of the side walls 16 and outer end wall 18. An upright wall 20 is spaced from said inner end wall 19 and forms part of a transversely disposed housing 20^a at the inner end of the frame for enclosing the drive gearing for the rotary brushes, as will presently appear.

The rotary brush elements 12 and 13 each consists of alternately arranged rows of rubber fingers 22, 22 and bristles 23, 23 extending from a hub 24a. Said hub may also be of rubber formed integrally with the fingers as by molding, and the inner ends of the bristles may also be molded in the hub. The elements 12 and 13 are preferably tapered longitudinally in a generally frusto conical form, and are mounted with their smaller, inner ends terminating just short of their respective shafts, so that when mounted in operative

position in the holder, the smaller ends of the two brush elements are closely adjacent each other in laterally offset but mutually overlapping relation, as clearly seen in Figure 3. A substantial portion of the peripheries of the two brush elements projects above the rim of said frame in position to engage the teeth and gums as said brush elements are rotated.

The drive connections for rotating the shafts 14 and 15 include a drive shaft 27 extending through the handle 11, and power-driven as through suitable flexible drive connections from a remotely disposed motor (not shown). The drive shaft 27 has a pinion 28 thereon, disposed in the lower part of the gear housing 20^a at the inner end of the frame 10. A pair of gears 29, 30 have shafts 31, 32, respectively, rotatably supported at opposite ends in the end wall 19 and the upright wall 20 of said gear housing, the inner ends of shafts 31 and 32 extending through the latter wall for connection with the ends of the brush element shafts 14 and 15, respectively. The pinion 28 meshes with one of the gears 29, and the latter gear meshes with its companion gear 30, as shown in Figure 4.

The shafts 14 and 15 carrying the brush elements 12 and 13 are mounted for detachable connection with the shafts 31 and 32 in like manner, as follows:

Shaft 15 has a longitudinally projecting tongue 33 at each end thereof, either one of which is adapted to fit in a transverse slot 34 formed in the exposed end of shaft 32. Similarly, shaft 14 has tongues 35, 35 at opposite ends adapted to fit in a slot 36 formed in the exposed end of shaft 31. Since the two shafts 14 and 15 are of the same length, it will be understood that said shafts are reversible and interchangeable with each other merely by removing said shafts and mutually reversing them end to end, or exchanging their relative positions in the frame. For this purpose both ends of shafts 14 and 15 are formed with shouldered end portions 37, 37, either one of which is adapted to fit in holes 38, 38 formed in spaced relation in bearing supports 39, 39 suitably mounted on the outer wall 18 of the frame. In the preferred form shown, said bearing supports consist of spring-like plates projecting downwardly and inwardly from a common cross member 40 mounted on the end wall 18, so that either of said bearing supports will yield outwardly under pressure, and thus permit ready insertion or removal of the brush element shafts when desired.

A plurality of apertures 41 may be provided in

the bottom and sides of the frame or holder 10 so as to facilitate washing of the device. The use and operation of a tooth brush constructed as above described will now be apparent.

The two brushes 12 and 13 are arranged so that the exposed peripheral portions thereof rotate in opposite directions, toward each other. The frame or holder forms a shield for one side of the rotating brushes, so that the device can be readily inserted in the mouth with the brushes in the desired localized engagement with the teeth and gums. It will be understood that the rubber fingers are especially adapted for massaging the gums, while the fiber tufts are primarily intended for cleaning the tooth surfaces. Since the brushes rotate toward each other the gums will be massaged by the rubber fingers in the accepted direction, that is to say, longitudinally of and toward the tooth.

Due to the offset relation of the two brushes 12 and 13, they are both disposed most compactly in the frame or holder so as to make a relatively small device which can readily be inserted and manipulated in the mouth.

Due to detachable mounting of the brushing elements and their respective shafts, their relative positions can be changed at will, either by reversing them end to end, or by exchanging their relative positions within the frame or holder. Also, either of the brushing elements can be removed if desired, so that a single element will be used at one time.

By reason of the arrangement of the leaf springs 39, 39, with their free outer ends extending toward the open side of the frame 10, it will be observed that the outer ends of the brush shafts 31 and 32 can be quickly detached by pressing their respective springs outwardly with the finger. In reassembling the shafts in place, it is only necessary to insert the inner end of the shafts in their recesses 34 or 36 and then spring the outer end of the shaft into the hole 38 of the opposed spring leaf bearing support 39 by pressing the shaft inwardly against the yielding inner face of said bearing support. As soon as the shouldered end portion 37 of the shaft registers with the hole 38 in the spring support, said spring support will immediately snap into proper bearing relation to the shaft, as shown in Figures 1 and 3.

Although I have shown and described one particular embodiment of my invention, it will be understood that I do not wish to be limited to the exact construction shown and described, but that various changes and modifications may be made without departing from the spirit and scope of my invention as defined in the appended claim.

I claim:

- 10 In a power-operated tooth brush, an open-sided frame, a pair of coupling members mounted at one end of said frame, power-operated means for rotating said coupling members in opposite directions, a pair of bearing supports at 15 the opposite end of said frame comprising two leaf-springs each having one end fixed on said frame and the other free end extending toward the open side of said frame, said free end having an aperture therein for receiving the outer end of its respective shaft in detachable bearing relation, and two rotary brush elements adapted to be disposed in exposed end-to-end laterally offset relation with each other, each having similar bearing and connecting means at both ends thereof adapted for selective engagement either with said coupling members or with said bearing supports; whereby said brush elements may be reversed end to end or interchanged between upper and lower positions in said frame.

PAUL H. BLAIR.
